(57) **CLAIM**

The ornamental design for a piezo nest having a vial track, as shown and described.

DESCRIPTION

FIG. 1 is a front plan view of a piezo nest having a vial track;
FIG. 2 is a left plan view thereof;
FIG. 3 is a rear plan view thereof;
FIG. 4 is a right plan view thereof;
FIG. 5 is a top plan view thereof;
FIG. 6 is a bottom plan view thereof;
FIG. 7 is a bottom left perspective view thereof;
FIG. 8 is a top, left, rear perspective view thereof; and,
FIG. 9 is a top, right, front perspective view thereof.
The broken lines of the drawings form no part of the claimed design.
